UNITED STATES PATENT OFFICE.

ARTHUR K. TAYLOR, OF BALTIMORE, MARYLAND, ASSIGNOR TO R. HOE AND CO., OF NEW YORK, N. Y., A CORPORATION OF NEW YORK.

PRINTING-MACHINE.

1,172,752.

Specification of Letters Patent. Patented Feb. 22, 1916.

Application filed August 5, 1910. Serial No. 575,785.

To all whom it may concern:

Be it known that I, ARTHUR K. TAYLOR, a citizen of the United States, residing at Roland Park, Baltimore, State of Maryland, have invented certain new and useful Improvements in Printing-Machines, fully described and represented in the following specification and the accompanying drawings, forming a part of the same.

10 This invention relates to improvements in printing machines, and more particularly to that class of printing machines intended to print on sheets of different lengths, the sheets being cut from a web.

15 Machines have been heretofore used which print upon sheets cut from a web, the machines including cutting devices which operate to cut sheets of different or varying lengths. In such machines it has been 20 customary to bring the sheets, after they are cut, to a stop, in order to properly register them with respect to the sheet taking devices which are to subsequently take them, these sheet taking devices being mounted 25 either on one of the cylinders of the printing couple or on an intermediate feeding cylinder. With such machines, particularly when they are run at high speeds, difficulty has been experienced in properly registering 30 the sheets against the stop, because of the short time in which the registering operation has to be effected.

The present invention has for one of its 35 objects to produce a printing machine employing a cutting mechanism operating to cut sheets of different lengths, the sheets being delivered on the run from the cutting to the printing mechanism, the necessity for stopping the sheets for registration being 40 avoided.

A further object of the invention is to produce an improved mechanism for handling sheets in printing machines in which sheets of different lengths are cut by a cutting mechanism and delivered to suitable sheet taking devices, the mechanism including means for varying the time of operation of the sheet taking devices, in accordance with the varying lengths of the sheets.

50 A further object of the invention is to produce an improved mechanism for handling sheets which includes a cutting mechanism adapted to cut sheets of different lengths from a web and a sheet taking mechanism, the sheet taking mechanism operat-

ing to take the head of the sheet at the time the cutting mechanism operates whatever be the length of the sheet cut.

The invention also includes certain other improvements not necessary to specifically refer to, but which will be hereinafter pointed out.

With these and other objects not specifically referred to in view, the invention consists in certain constructions, and in certain parts, improvements and combinations as will be hereinafter fully described and then specifically pointed out.

Referring to the accompanying drawings:—Figure 1 is a diagrammatic side elevation, partly in section, of so much of one form of printing mechanism embodying the invention as is necessary to an understanding thereof. Fig. 2 is a detail plan view, partly in section, of certain adjusting mechanism for sheet taking devices which may be employed. Fig. 3 is a detail side elevation, illustrating more particularly the cutting mechanism. Fig. 4 is a view of the mechanism shown in Fig. 3, the position of the observer being indicated by the arrow 4 in said figure.

Machines which include the invention in its entirety will contain a cutting mechanism which is adapted to cut sheets of different or varying lengths, *i. e.* mechanism which may be set so as to cut sheets of different lengths, as required. While the construction of this cutting mechanism may be varied, in the particular construction illustrated, it embodies a cylinder 1 mounted on a shaft 2 supported in suitable bearings in the frame, the cylinder being provided with a knife 3. Coöperating with the cylinder 1 is a companion cylinder 4 mounted on a shaft 5, this cylinder being provided with a cutting wood 6. These cylinders are intergeared, as shown, the shaft 2 of cylinder 1 being provided with a gear, as 7, and the shaft 5 of the cylinder 4 being provided with a similar gear 8. In order to effect the cutting of sheets of different lengths, these cylinders are driven at varying speeds as the cutting members pass the cutting point. In the construction shown, this is effected by providing the shaft 5 with a crank arm 9 provided with a sliding block 10 which works between two cheek pieces 11 fast on the face of a gear 12 mounted on a short shaft 13

supported in a sliding bearing 14 suitably guided in the frame. This bearing has a downwardly depending boss 15 into which is threaded a screw 16 which passes downwardly through an opening in the frame and is secured against vertical movement by a washer 17. The screw is provided with a worm wheel 18 which engages with a worm 19 suitably journaled in the frame 5 and operated in any suitable manner, as, for instance, by a crank handle 20. As the shaft 13 and gear 12 are moved vertically, the block 10 is brought nearer to or farther from the center of rotation of the shaft, and, therefore, the speed of the cutting members at the cutting point is proportionately varied. The standard of the frame in which the shaft 13 is journaled may be supported, if desired, by a bracket 10 and 15 21 and through this bracket and the standard below it there may be tapped a stop screw, as 22, to determine the adjustment of the sliding bearing. The gear 12 is driven by a gear 23 which is run turn for 20 25 turn with the cylinder.

The particular machine illustrated operates upon a web which is shown as passing over a guide roller 24 and between a pair of variable length feed rollers 25 which 30 rollers may be intergeared and may be driven in any suitable way to present the web to the cutting mechanism. As shown, the lower one of the rollers 25 is provided with a gear 26 which meshes with a gear 35 27 mounted on a stud 28. This stud is secured in a slot 29 in the frame to enable the position of the gear to be shifted. This gear 27 is in mesh with a gear 29, bolted, as indicated at 30, to the face of a gear 31 40 running loose on the shaft 5. The gear 31 meshes with a gear corresponding in pitch diameter with the gear 23 and located in front of this gear as the same is shown in Fig. 1. It is apparent that by changing 45 the size of the gear 29', the feed rolls will be driven at varying speeds so as to present more or less web to the cutting cylinders. It will be understood, of course, that the web passes freely between the cutting cylinders, being nipped between them only at 50 the time of the cutting operation. This variable speed mechanism for the webs and for driving the cutting cylinders is well-known in the art and may be replaced by 55 any other suitable mechanism or mechanisms. Guides, as 32, of ordinary construction may be employed, if desired, between the variable feed rollers and the cutting cylinders.

60 In machines embodying the invention in its complete form, the sheets will be transferred on the run, that is to say, without being stopped, from the cutting mechanism to the printing mechanism. While this may 65 be accomplished in various ways, in the

particular construction illustrated, there is employed a sheet carrier consisting of a cylinder 33 mounted on a shaft 34, this cylinder 33 being provided with a gear 35 meshing with and driving the gear 23. 70 The cylinder 33, when employed, will be provided with sheet taking devices which may be of any suitable description. In the particular construction illustrated, these sheet taking devices consist of grippers 36 75 which may be operated by the usual tumbler block 37. The sheets in passing from the cutting mechanism to this carrier mechanism, when the same is employed, may travel over a guide 38, of usual type, supported on a bracket 39 extending from a cross-bar of the frame. Rolls 40 may be employed, if desired, in connection with this guide, these rolls, when employed, being arranged to run slightly faster than 80 the sheet, as is common in such constructions.

In order to properly present the sheet to the cylinder 33 the end of the guide which is nearer the cylinder may be turned up, 90 as indicated at 41, and there may be employed in connection therewith rolls, as 42, 43, to control the sheet at this point.

When a transferring mechanism of the character referred to is employed, means 95 should be provided for varying the time of operation of the closing of the grippers, as it is obvious that the grippers should close at one time with one length of sheet and at another time with a different length. In the particular construction illustrated, the grippers are closed by a tumbler pin 44 mounted on an arm 45 fast on a toothed disk 46 loosely mounted on the shaft 34 before referred to. It is apparent that by 105 rotating the disk in one direction or the other the grippers may be caused to close at different points in the revolution of the carrier 33. The means for rotating the disk, when this construction is employed, may be 110 of any suitable character. As shown, the teeth on the disk are engaged by a worm 47 mounted on a shaft 48 supported on suitable brackets 49 extending inward from the frame, the shaft being operated in any suitable manner, as by a hand-wheel 50. Suitable pressure rolls, as 51, of ordinary construction, may be employed in connection with the cylinder 33 to hold the sheet in 115 contact therewith.

The printing mechanism employed in carrying the invention into effect may be of any suitable character. That illustrated 120 diagrammatically consists of a cylinder 52 provided with sheet taking grippers 53, 125 these grippers being closed on the sheet to take it from the grippers 36 by a cam, indicated at 54, and being opened to release the sheet by a cam, indicated at 55. The cylinder 52, in the construction shown, is an im- 130

pression cylinder, and coöperates with a printing cylinder, indicated at 56. The grippers on the cylinder 52 take the sheet from the grippers 36 and transfer it to grippers 57 on a cylinder 58 which cylinder may be a delivery cylinder or an impression cylinder coöperating with a printing cylinder, not shown, to give the sheet a second impression.

Changes and variations may be made in the construction by which the invention claimed is carried into effect. The invention claimed, therefore, is not to be limited to the particular construction hereinbefore described and illustrated in the accompanying drawings.

What is claimed is:—

1. The combination with a printing mechanism, of means for cutting sheets of different lengths, means including a cylinder having sheet taking devices for transferring sheets from the cutting mechanism to the printing mechanism, and means for varying the time when said sheet taking devices take the sheets.

2. The combination with a pair of cutting cylinders, of means for feeding a web thereto, means for varying the time of operation of the cutting cylinders to cut sheets of different lengths, sheet taking mechanism including devices for seizing the head of the sheet, means for causing said devices to seize the head of the sheet at the time the cutting cylinders operate, and a printing mechanism to which the sheets are delivered.

3. The combination with a constantly rotating cylinder having sheet taking devices, of continuously running means for delivering sheets of different lengths thereto, and means for varying the time at which the sheet taking devices operate to take the sheet to enable the different lengths of sheets to be properly taken.

4. The combination with a constantly rotating cylinder having sheet taking devices,

of continuously running means for cutting and delivering thereto sheets of different lengths, and means for varying the time at which the sheet taking devices operate to take the sheet to enable the different lengths of sheets to be properly taken.

5. The combination with a cylinder having sheet taking grippers, of means including a cutting mechanism driven at varying speeds for delivering sheets of different lengths to the cylinder, gripper closing and opening devices, and means for varying the sheet taking position of the gripper closing devices to enable the different lengths of sheets to be properly taken.

6. The combination with a cylinder having sheet taking grippers, of means including a cutting mechanism driven at varying speeds for cutting and delivering to the cylinder sheets of different lengths, closing devices for the grippers, opening devices for the grippers, and means for varying the time at which the closing devices operate to take the sheet to enable the different lengths of sheets to be properly taken.

7. The combination with a cylinder having sheet taking grippers, of means for operating the grippers to take the sheet, said means including a rotatable carrier on which the operating means is mounted, whereby the point in the revolution of the cylinder at which the sheet is taken may be varied to enable the different lengths of sheets to be properly taken, and means operating at a fixed point in the revolution of the cylinder to cause the grippers to release the sheet.

In testimony whereof, I have hereunto set my hand, in the presence of two subscribing witnesses.

ARTHUR K. TAYLOR.
